PAIR OF SPECTACLES

Jack Bloch, Leominster, and Vitalino Marchi, Concord,
Mass., assignors to Foster Grant Co., Inc., Leominster,
Mass., a corporation of Delaware

Filed Dec. 30, 1966, Ser. No. 5,237

Term of patent 14 years

(Cl. D57—1)

The drawing is shaded to indicate contrast.

We claim:

The ornamental design for a pair of spectacles, substantially as shown and described.
